UNITED STATES PATENT OFFICE.

LEWIS M. CLEMENT, OF MOUNTAIN LAKES, NEW JERSEY, AND JOHN F. NIELSEN, OF WINFIELD, NEW YORK, ASSIGNEES TO F. A. D. ANDREA, INC., OF NEW YORK, N. Y., A CORPORATION OF NEW YORK.

LOUD-SPEAKER MOTOR UNIT.

Application filed September 11, 1926. Serial No. 134,779.

Our invention relates to operating units for loud speakers, particularly to units for operating sounding boards or acoustic radiators for loud speakers usually employed with 5 radio receiving instruments.

One of the important elements entering into the faithful translation of electrical energy into sound waves is the unit for operating the sound board. It is important, 10 therefore, to properly arrange and construct the elements of the unit to secure the best results.

Our invention will be better understood by reading the following description taken in 15 connection with the accompanying drawings which illustrate one embodiment of our invention, and in which:

- Fig. 1 is a top plan view of the unit;
- Fig. 2 is a side elevation of the unit;
- Fig. 3 is a front elevation of the unit;
- Fig. 4 is a view on lines IV—IV of Fig. 1;
- Fig. 5 is a view on line V—V of Fig. 1;
- Fig. 6 is a sectional view on line VI—VI of Fig. 3;
- Fig. 7 is a sectional view on line VII—VII of Fig. 2 and

Fig. 8 is an enlarged view showing the soldered joints between the armature 19, operating tube 24 and member 25.

In the drawings the mounting plates 1 and 2 are the supporting means for the unit and may be of any suitable material, preferably of brass or aluminum. As best shown in Fig. 6, these plates support the unit by bolts 3 and 4. The bolts 3 and 4 pass through the mounting plates 1 and 2 and nuts 5 and 6 hold them in position. The bolts 3 and 4 are held in place against the ends 7 and 8 of a permanent magnet by bolts 9 and 10.

Pole pieces 11, 12, 13 and 14 of magnetic material, preferably silicon steel, and also laminated if desired, are held firmly against the ends 7 and 8 of the magnet by screws 15, 16, 17 and 18, which pass through face plates 22 and 23. The pole pieces 11 to 14 are tapered, as shown in Fig. 5. The narrow ends of pole pieces 12 and 14 and of 11 and 15 are placed close together and a magnetic armature 19 is held in position between the pole pieces by a spring 20 which is carried by bolts 21 carried by the face plate 23.

Surrounding the armature 19 are coils 24^a which are held in position between the pole pieces 11 to 14. The bobbins upon which the

coils are wound are preferably molded and 55 fit into the assembly and are supported by the bolts 21. They are made so that they do not touch the armature or armature supporting spring.

Connected with the armature 19 is a tube 24 60 which is connected with a member 25 having a peculiar shape, which will now be described. There is a flattened part 26 on member 25 which is attached to the face plate 23 by screws 27 and washer 27^a. This is a rigid 65 support. To the end of the member 25 is attached the tube 24 and an operating rod 28 is attached to the member 25 between the place of attachment of the tube 24 and the screws 27. The place of connection of rod 28 to 70 member 25 depends upon the type of radiator used and the frequency at which maximum power is to be delivered to the radiator. The member 25 vibrates in response to vibrations imparted by tube 24 and in order that there 75 shall be as little resistance as possible to such vibrations the metal of member 25 is aligned and arched transversely of the member 25 at 29, around which part the member vibrates. In order to render the member 25 as rigid as 80 possible from the part 29 to the end it is arched longitudinally along the line 30 from the point 29 to the free end of the member. By the construction shown the member 25 has a maximum rigidity, minimum resistance to 85 movement and minimum mass. The driving tube 24 is flattened at its lower and upper ends so that the resistance to bending caused by armature 19 and member 25 will be a minimum, while the lateral stiffness will be preserved. The metal of the tube 24 is flattened 90 so that it lies in a plane at right angles to the longitudinal axis of the armature. This is very important as it improves the efficiency and response characteristics by reducing the 95 resistance to bending as described. It also prevents transverse vibration of the tube which would absorb energy at a vibration frequency. All of these are desirable qualities in a unit of this type.

The vibrations of the armature 19 are transmitted through the member 25 to the rod 28 and thence to a sounding board or radiator of any desired construction. The rod 28 has a covering 31 of dampening material 105 to prevent lateral vibrations.

The face plates 22 and 23, the mounting plates 1 and 2 and the pole pieces 11, 12, 13

and 14 are preferably all punch press parts. These are held together by screw machine parts.

The transformer member 25 is made to combine stiffness with minimum weight and insure that bending will occur only at 29. The holes in the member 25 for the driving tube 24 are extruded as shown in order to form a cylindrical opening. The transformer member 25 is held against its mounting plate by a washer 27^a as shown.

The armature driving rod which is made with two flat places, one near each end, to reduce the force required to bend the otherwise stiff rod when the armature and transformer rotate around their bearings is held at both ends by soldering and riveting. One end of the rod is forced through an opening in the end of the armature and is then riveted and soldered. The other end passes through the cylindrical opening in the member 25 and is soldered. This means of attaching the rod to the armature and member 25 cuts down the mass and increases the efficiency in addition to giving good joints.

In order to prevent lateral vibration of the armature driving rod, a spider 40 of rubber or other suitable material may be mounted so that if lateral vibrations start, they will be damped by the spider.

The circuit for the electrical coils 24^a is through wires 32 and 33 which lead to connectors 34 and 35 and thence to the ends of the coils which are in series, and their effects are additive. In the use of the device in a loud speaker for radio the wires 32 and 33 are connected to the usual output circuit of the receiver.

The supporting members 1 and 2 have elongated openings 36 and 37 for the purpose of adjusting the position of the unit.

Our invention has many advantages which will be apparent to those skilled in the art.

We claim:

1. In a loud speaker motor unit, the combination of a permanent magnet, side members of non-magnetic material attached to the ends of said magnet, pole pieces for said magnet carried by said side members and held firmly against the ends of said magnet, a resiliently supported armature between said pole pieces, two coils around said armature and means for connecting said armature with the diaphragm.

2. In a loud speaker motor unit, the combination of a permanent magnet, side members of non-magnetic material attached to the ends of said magnet, pole pieces for said magnet carried by said side members and held firmly against the ends of said magnet, said pole pieces being tapered and the tapered ends of the pieces in the same side of the magnet being adjacent each other, an armature resiliently supported between said pole pieces and held in a neutral position, two coils surrounding said armature and means connecting the armature with the loud speaker diaphragm.

3. In a loud speaker unit, the combination of a permanent magnet, flat pole pieces held against each side face of each end of said magnet, a flat face plate of non-magnetic material bridging the ends of said magnet and lying alongside said pole pieces and mounting plates parallel with said face plates.

4. In a loud speaker unit, the combination of a permanent horse-shoe magnet, magnetic pole pieces on the side faces of said magnet and extending into the open end of the horse-shoe, said pole pieces being pointed at their free ends, a face plate lying along each pair of pole pieces, an armature having its ends extending between the pointed ends of said pole pieces, electrical coils surrounding the armature and mounted on molded bobbins fitting between said pole pieces and means for resiliently supporting said armature.

5. In a loud speaker mechanical transformer, the combination of an armature, a movable member, an actuating member connecting said armature to said movable member, the joint between said actuating member and movable member being formed by extruding the metal of said movable member to form a cylindrical opening into which said actuating member is riveted and soldered.

6. In a loud speaker motor unit, the combination of an armature, a movable member, an actuating member connecting said armature with said movable member, said actuating member being rigid longitudinally and transversely except in a plane passing through the longitudinal axes of said armature and said actuating member, said armature having an opening through which said actuating member passes and is riveted and soldered.
